L. C. DOANE

LIGHTING FIXTURE

Filed Sept. 17, 1924

UNITED STATES PATENT OFFICE.

LEROY C. DOANE, OF MERIDEN, CONNECTICUT, ASSIGNOR TO THE MILLER COMPANY, OF MERIDEN, CONNECTICUT, A CORPORATION OF CONNECTICUT.

LIGHTING FIXTURE.

Application filed September 17, 1924. Serial No. 738,148.

The object of this invention is the construction of a lighting fixture which is especially adaptable for dining room domes, or any room where an intense circle of pleasant light is desired in conjunction with a lesser amount of general illumination.

The figure is an elevation partially in section in which 1 is the source of light, the socket of which is housed in a holder 2, having arms 3, adapted to support a glass bowl 4 in the manner shown. The bowl is here shown as composed of three zones, an upper downwardly flaring zone 5, an intermediate straight sided zone 6 and a lowermost flat zone 7, which has a base 8 of the form shown. The comparative translucency of this bowl varies in the various zones, the intermediate zone being preferably white enamelled inside. The top and bottom zones are of crystal glass sprayed with a light coating of enamel to admit of greater translucency when compared with the intermediate zone for purposes hereinafter set forth. A cylindrical ring of aluminum 9 has its upper rim 10 turned back to fit over the upper edge 11 of the bowl and under the turned in portion 12 of the holder arms. The bottom of this ring is turned inward to form a polished elliptical reflector 13 fitting around the source.

Such domes are usually suspended over dining room tables. Typical rays *r* and *s* from the source striking the inner surface of polished reflector 13 will be reflected in direction *r'* and *s'* and pass through the base 8 of the bowl to illuminate the tabletop underneath. So too ray *t* is transmitted without reflection through the base. There is a sufficient quantity of the light which escapes the action of the reflector to illuminate the bowl generally, and the size and general contour of the reflector 13 can be varied to give a larger or smaller quantity of light on the table and a comparative brightness of the balance of the bowl.

It will also be observed that zone 6 is relatively denser than zones 5 and 7; the eye of those sitting around the table is on a level with this zone and its comparative darkness makes an effective screen when the eye is directed to the bowl itself. The light through the base 8 is reflected back by the surface of the table and to a certain extent plays a part in the general illumination. The upper zone 5 is of greater translucency

than zone 6, so that it can effectively distribute such rays as reach its inner surface either directly from the source or by way of various interior surface reflections. This zone is above the line of vision of those seated around the table and therefore cannot be unpleasant to them. The rays transmitted by this zone although in diminished quantity contribute to a certain degree to the general illumination of the ceiling and upper parts of the room.

An additional feature and one which renders the fixture of additional use is the fact that the reflector can be removed and the fixture employed for general illumination. Various types of glass and metal can be substituted for the one proposed as long as the general idea is carried out. The holder parts can also be varied at will as their form is not an intrinsic part of the invention and the surface of the bowl may be decorated entirely or in part as desired.

Reflector 13 is preferably of an elliptical contour so that a secondary focus 14 is created by rays reflected from the primary focus 15, as shown in the drawing.

I claim:

1. A lighting fixture comprising a light source, a glass bowl and a reflector, the bowl having a downwardly flaring upper zone and a comparatively flat translucent base and an intermediate denser zone, the reflector being adapted to reflect rays from the source through the base of the bowl, in a sharply defined circle of light.

2. A lighting fixture comprising a light source, a glass bowl and a reflector, the bowl having a downwardly flaring upper zone and a comparatively flat translucent base and an intermediate denser zone, the upper zone housing a cylindrical ring having an upwardly and inwardly converging base forming a reflector around the source and adapted to reflect rays from the source through the base of the bowl.

3. A lighting fixture comprising a light source, a glass bowl and a reflector, the bowl having a downwardly flaring upper zone and a comparatively flat translucent base and an intermediate denser zone, the upper zone housing a cylindrical ring surrounding the source having its upper rim turned back to encircle the upper edge of the bowl with its base turned upwardly to form a reflector around the source and adapted to reflect

rays from the source through the base of the bowl.

4. A lighting fixture comprising a light source, a reflector and a totally enclosing glass bowl, the reflector being of cylindrical form surrounding the source and having its base turned inwardly and upwardly to form a reflector extending for a distance around the source, the enclosing bowl consisting of 10 an upper flaring portion and a comparatively flat translucent base, the reflector being adapted to reflect rays from the source through the base of the bowl.

5. A lighting fixture comprising a light

source, a glass bowl and an elliptical reflector with one of its foci at the center of the source, the bowl being of the totally enclosing type surrounding the reflector and having a comparatively flat translucent base the relative proportions of the reflector and base of the bowl being such that the second focus of the ellipse is in the base of the bowl.

Signed at Meriden, in the county of New Haven and State of Connecticut, this 11th 25 day of September, 1924.

LEROY C. DOANE.
